UNITED STATES PATENT OFFICE.

EARL B. SCOTT, OF JOLIET, ILLINOIS.

GUARD-RAIL.

1,157,426.

Specification of Letters Patent. Patented Oct. 19, 1915.

Application filed April 17, 1915. Serial No. 22,055.

To all whom it may concern:

Be it known that I, EARL B. SCOTT, a citizen of the United States, and resident of Joliet, county of Will, and State of Illinois, 5 have invented certain new and useful Improvements in Guard-Rails, of which the following is a specification.

Wherever railways are supported by trestle-work, such as bridges, elevated structures and the like, it is necessary to place guard rails transversely of the ties and parallel to the rails to prevent the cars, engines, etc., in case of derailment, from leaving the trestle-work and incurring great damage.

15 Also the guard rails aid in preventing the ties from creeping and from being relatively displaced. The present guard rails are of wood and are bored and fitted to place after being delivered on the trestle-work. The 2 wooden guard rails split and decay, and the bolt holes become enlarged, permitting movement, and soon the guard rails lose their strength to oppose shocks to which they are subjected. Also the ties are prevented from 25 movement only by the bolts which pass through the ties and guard rails.

My invention includes a steel guard rail provided with downwardly extending members to act between ties and thereby hold 30 them in their relative positions without having to depend upon the bolts through the ties and guard rails.

One of the objects of my invention is to provide a guard rail which can be formed 35 ready for application at its place of manufacture, making the drilling of the holes in the ties the only work necessary to be done on the trestle-work.

Other objects will be apparent from the 40 description.

I prefer to employ a guard rail of a rolled section having the tie-spacers integral therewith. Holes for receiving the bolts are formed at proper intervals at the mill where 45 the rails are made. This type requires no fabrication and is ready for application as delivered.

Another type is formed from standard or special channel bars, the runners having 50 short pieces of channels riveted thereto to form the tie-spacers. The channel portion of the runner may be filled with concrete,

asphalt or like substances, to prevent water lodging therein.

Further novel features will be seen by 55 referring to the drawings, in which:

Figure 1 is a plan view of a fragmentary portion of trestle-work showing ties, a rail, and a guard rail constructed in accordance with my invention, Fig. 2 is an end view of 60 Fig. 1, showing the guard rail with tie-spacers and the application to the ties, Fig. 3 is a plan view of a fragmentary portion of trestle-work showing a modified form of guard rail, Fig. 4 is an end view of Fig. 3, 65 and Fig. 5 is a sectional view on line 5—5 of Fig. 3 showing a filling material in the channel of the guard rail.

10 is a rail fastened to ties 11 by any suitable means. 12 is a guard rail embodying 70 my improvements, bolted, as shown, near the ends of ties 11. 13 are bolts fastening guard rail 12 onto ties 11. As will be observed, the guard rail 12 has a flat top and therefore can not retain water or snow. Two 75 guard rails 12 are shown joined at 14. Between the ties 11 are downwardly-projecting tie-spacers 15 integral with guard rail 12 and adapted to prevent the ties from bunching. 80

In Figs. 3, 4, and 5 another type of guard rail 16 is shown formed of a standard or special channel section with tie-spacers 17, also of channel section, riveted thereto. The length of the channel sections used for tie-spacers is the same as the width of the guard rail 16. Bolts 16^a fasten the guard rail 16 to the ties 11 in the same manner as shown in Figs. 1 and 2. Abutting guard rails are fastened by any approved joint. 85 One form is shown at 18 and consists of a plate 19 riveted to an end of one guard rail 16 and adapted to be bolted to the end of a contiguous guard rail. As shown in Fig. 4, the bolts used for securing the tie plate 19 90 to the contiguous guard rail may be used to hold the tie-spacer 17 as shown at 20. If desired, concrete, asphalt or like materials, may be put into the U-shaped portion of the channel forming the guard rail 16 to prevent 95 water, etc., from lodging therein, as shown at 21.

While I have shown a channel section in Figs. 3 and 4, I do not consider my inven-

tion limited thereto. The use of any standard or special section as and for the purpose described I consider as being within the spirit of my invention.

5 Having thus described my invention, what I claim as new and desire to secure by Letters Patent is:

1. In a device of the class described, the combination with railway ties and rails thereon, of metal guard rails adapted to be bolted to said ties parallel to said rails and provided with integral, downwardly-extending tie-spacing members tightly fitted between adjacent ties, bolts, said bolts adapted to extend through said ties and said guard rails and project above the guard rails, and means for securing together the ends of adjacent guard rails.
2. In trestle-work for railways, the combination of ties, railway rails thereon, and metal guard rails parallel to said railway rails and lying on said ties, bolts fastening said guard rails to said ties, tie-spacing members extending below the bottom surface of said guard rail and between adjacent

ties, and means for fastening together the ends of contiguous guard rails, substantially as described.

3. In a device of the class described, the combination with railway ties and rails thereon, of metal guard rails adapted to be bolted to said ties parallel to said rails and provided with integral downwardly-extending tie-spacing members fitting between adjacent ties, and means for securing together the ends of adjacent guard rails, substantially as described.

4. In a tie-spacing device, the combination with ties, railway rails secured thereto, of metal guard rails bolted to said ties parallel to said railway rails, and metal tie-spacing members extending downwardly below the bottom surface of said guard rails and between adjacent ties, and integral with said guard rails, substantially as described.

Signed at Joliet, Illinois, this 26 day of March, 1915.

EARL B. SCOTT.
